UNITED STATES PATENT OFFICE.

CLARE A. WETZELL, OF STERLING, ILLINOIS.

DESIGN FOR A WHEEL-BEARING FIGURE TOY.

Application filed March 27, 1928. Serial No. 26,031. Term of patent 3½ years.

To all whom it may concern:

Be it known that I, CLARE A. WETZELL, a citizen of the United States, residing at Sterling, in the county of Whiteside and State of Illinois, have invented a new, original, and ornamental Design for a Wheel-Bearing Figure Toy, of which the following is a specification, reference being had to the accompanying drawing, forming a part thereof.

Fig. 1 is a side perspective view of my toy; and

Fig. 2 is a front perspective view of the toy.

I claim:

The ornamental design for a wheel bearing figure toy as shown.

CLARE A. WETZELL.
